UNITED STATES PATENT OFFICE.

OTTO KRAUS, OF NEW YORK, N. Y., ASSIGNOR TO KRAUS ENGINE COMPANY, OF NEW YORK, N. Y., A CORPORATION OF NEW YORK.

APPARATUS FOR PRODUCING WORKING FLUIDS.

1,032,550.

Specification of Letters Patent. Patented July 16, 1912.

Application filed March 18, 1911. Serial No. 615,406.

To all whom it may concern:

Be it known that I, OTTO KRAUS, a citizen of the United States, residing in the borough of Manhattan, in the city, county, 5 and State of New York, have invented certain new and useful Improvements in Apparatus for Producing Working Fluids for Motors, of which the following is a specification, reference being had to the accompanying drawings.

This invention relates to improvements in apparatus for producing working fluids for motors; and an object of this invention is to provide an apparatus of the character just 15 mentioned which will be simple and efficient in practice.

Another object of this invention is to provide an apparatus of this character in which complete combustion of the fuel will take 20 place.

A third object of this invention is to provide an apparatus of this character with a steam generator and superheater and so to construct and arrange the same that the 25 working fluid delivered therefrom will be at a temperature which will allow water-jackets on the motors to be dispensed with, which will be non-injurious to the parts of the latter with which the working fluid 30 comes into contact and which will, nevertheless, be sufficiently high to make the working of the motor highly efficient.

A fourth object of this invention is to control the passage of the products of combustion from the combustion chamber to the generator and superheater, as by a valve, and to provide means for automatically 35 keeping this valve comparatively cool.

A fifth object of this invention is to provide the generator and super-heater with means for breaking up and impeding the 40 passage of the stream of water, steam and hot gases which flows thereinto and for transferring the heat from the hot gases 45 in the stream to the water and steam, whereby the latter are transformed into steam gas and the hot products of combustion are cooled.

Other features of this invention will be 50 set forth in the description which follows.

In the drawings illustrating the principle

of this invention and the best mode now known to me of applying that principle, Figure 1 is a central longitudinal section through my new apparatus; and Fig. 2 is a 55 section on the line 2—2 of Fig. 1.

The wall *a* of the casing *b* is almost entirely hollow and the annular space *c* between the inside and the outside of this hollow wall is connected by the water-supply 60 pipe *d* with a source of water supply of any suitable character, the water being forced in under pressure. The wall *a* encloses or surrounds the combustion chamber *e* within which is contained refractory material, such as pieces of fire-brick *f*. Near the inlet end of the combustion chamber *e* there is mounted in the wall *a* an igniter *g* of any suitable description. To the wall *a* of the casing *b* near the inlet end of the combustion chamber *e* there is fastened, by the screw ring *h*, the casing *i* of a fuel-feeding device *j*. To the chamber *k* within the casing *i* air is led under pressure by the pipe *m*. Within the chamber *k* there is mounted 75 a chambered spraying device or atomizer nozzle *n*; and within the latter there is mounted a fuel-nozzle *o*, in which is a needle valve *p*. In the lower part of the casing *i* there is formed a chamber *q* into which 80 liquid fuel is forced by the pump plunger *r'* of the pump *r*. Between the head *s* of the plunger *r'* and the pump cylinder *r''* there is mounted a coil spring *t*. The liquid fuel is drawn by the pump *r* from the oil-tank (not shown) through the fuel-inlet pipe *u* and past the ball check-valve *w* and is forced by the pump past the ball check-valve *w'* into the oil-reservoir *q*. In the latter there is fitted the upper end of an overflow pipe *y* in which is mounted a ball-check valve *w''* and which communicates at its lower end with the interior of the pump-cylinder *x''* within which reciprocates the pump plunger *x'*, which is similar in all 95 respects to the pump plunger *r'* and is, like the latter, controlled by a coil spring *t*. The outlet *z* from the pump *x* is controlled by the ball check-valve *z*, which is normally held on its seat by the coil spring *z*. Compressed air entering through pipe *m* will 100 normally flow through the opening *n'* into

the atomizer *n* and from the latter through the L-shaped air passage *n''* to the fuel reservoir *q*, wherein it will exert a pressure upon the surface of the liquid fuel. When 5 the air rushes out of the atomizer-nozzle *n*, this air-pressure will, due to the suction therein produced, force the liquid fuel through the fuel passage 5 into the fuel-nozzle *o* and past the needle valve *p* out into 10 the atomizer *n*, where it will mix with the air from the pipe *m*. This mixture of liquid fuel and air will be sprayed from the atomizer *n* into the inlet end of the combustion chamber *e*, where it will be ignited by 15 the igniter *g*. By manipulating the screw-plug *o'*, the flow of air through the annular passage *n** and through the atomizer-nozzle *n* may be controlled so as to vary the volume of air which is fed direct to the 20 combustion chamber *e* through the annular passage *n** and the volume of which passes through the opening *n'* to atomize the fuel.

On the upper end of the casing *b* there is mounted the casing *g* of the steam generating-and-superheating chamber *7*. The top 25 of the casing *b* is closed by a grating or foraminated plate *8* which forms part of the bottom of the casing *g* and, therefore, of the generating chamber *7*. The casing *g* is formed with an opening *9* which is normally closed by the handhole cover *10*. The chamber *7* contains small pieces *11* of any suitable material and these pieces are of such size as to offer a large heating surface 30 and are at the same time not so small as to impede unduly the passage of the fluid through the chamber. I have found that a metal chain having small links *11* is well adapted for the purpose. The outlet end 35 of the chamber *7* is provided with a foraminated diaphragm *8'*, which closes that end of the chamber against any danger of the chain being drawn therefrom. As will be understood from an inspection of Fig. 40 45 1, the diaphragm *8* prevents the chain falling out of the casing *g* at that point.

The length of the combustion chamber *e* is sufficiently great to insure the complete combustion of the liquid fuel, and the products of combustion on leaving the combustion chamber are at a high temperature. These highly-heated products flow past the cup-like valve *12* which closes the outlet 50 end of the combustion chamber and, as a result, the valve *12* tends to become very highly heated.

To keep the valve *12* comparatively cool, the following arrangement of parts is provided and is an important feature of this 60 invention: The annular water-jacket *c* is open at its top, which lies above the valve *12*. That portion *8''* of the diaphragm *8* which lies directly above the water-jacket *c* is imperforate. The flow of water in the 65 water-supply pipe *d* is so regulated that

there will be a constant overflow of water from the open upper end of the water-jacket *c*. Some of the water which overflows from the latter will fall into the cup-like valve and will maintain the same in a cool condition, despite the extremely high temperature of the gases issuing from the combustion chamber *e*. Part of the water which splashes upwardly from the open top of the water-jacket *c* will strike against the imperforate portion of the diaphragm *8* and will be deflected downwardly into the cup-like valve. The upward movement of the latter is limited by a finger *13* which extends downwardly from the diaphragm *8*. The highly-heated products of combustion flowing past the valve *12* from the combustion chamber *e* will mix with the steam and water flowing from the open top of the water-jacket *c*; and this mixture of gas, steam and water will pass through the foraminated part of the diaphragm *8* into the steam generating and superheating chamber *7*. The dimensions and arrangement of the latter are such that the water and steam will be transformed into steam gas, while the products of combustion will be cooled, so that the mixture of these products and the steam gas which flows from the chamber *7* through the pipe *14* to the motor and which is designed to serve as a working fluid for the same will be at a temperature so low that no injury will be done to the working parts of the motor with which the mixture comes into contact and the use of water-jackets may be dispensed with. The working fluid will, nevertheless, be of a sufficiently high temperature to insure the motor working at high efficiency. The chain-links *11* break up and retard the stream of water, steam and highly-heated gases flowing into the chamber *7* through the diaphragm *8*. These chain links *11*, moreover, absorb heat from the highly heated gases and then give it up again to the water and steam, transforming the same into steam gas and bringing the whole mixture to the proper temperature for efficient working in the motor to which it is supplied through the pipe *14*. The pressure of the spring *4* on the ball valve *3* is of such degree that the ball valve *3* will not be raised by the pressure of the compressed air. However, should any liquid fuel overflow from the oil-reservoir *q*, it will be drawn past the ball check-valve *w''* and, after a sufficient quantity has accumulated in the pump cylinder *x''*, it will, since it is practically incompressible, be forced past the spring-pressed ball-valve *3* and will flow back to the oil-tank (not shown). The pump plungers *r', x'* are driven by the beam *15* in any suitable manner. If desired, the water-supply pipe *d* may, in the case of a condensing engine, be connected 130

with the latter and an increase of efficiency obtained by the preheating of the water supplied to the water-jacket *c*. A suitable drain-pipe *e'* is provided for the combustion chamber *e*.

The operation of my new apparatus may be briefly described as follows: Liquid fuel, such as crude oil, is drawn by the pump plunger *r'* through the fuel-inlet pipe *u* past 5 the ball-valve or check-valve *w* and is forced into the oil reservoir *q*. From the latter the liquid fuel is forced by air-pressure through the fuel-passage *s* into the fuel-nozzle *o* and past the needle-valve *p* out 10 from the nozzle into the atomizer *n*. The mixture of air and fuel is sprayed from the atomizer into the combustion chamber *e*, where it is ignited by the igniter *g*. The combustion heats the pieces of refractory 15 material *f* to an intense heat. After the refractory material has become incandescent, the fuel will ignite immediately on contact therewith and will burn completely, whereby perfect combustion will be attained. 20 The electric igniter *g* may then be cut out and the apparatus will continue its operation. The heat generated by the combustion also raises the water in the water-jacket *c* to a high temperature. The cup-like valve 25 12 is kept comparatively cool by the water which splashes over from the water-jacket *c* and which is caught in the cup-like valve 12. The products of combustion from the combustion chamber *e* mix with the water and 30 steam from the water-jacket *c* and this mixture flows through the foraminated diaphragm *g* into the steam generating-and-superheating chamber 7. The chain links 35 11 in the chamber 7 serve to break up and steam from the water-jacket *c* and this mixture flows through the foraminated diaphragm *g* into the steam generating-and-superheating chamber 7. The chain links 11 in the chamber 7 serve to break up and 40 impede the passage of the mixture of water, steam and products of combustion. As hereinbefore stated, the hot gases give up some of their heat to the chain links 11 and are, therefore, cooled. The heat absorbed 45 by the chain-links is given up by them to the water and steam, which are thus transformed into steam gas; and the products of combustion and the steam gas flow through the grating *g* and the pipe 14 to the motor, 50 which may be a single-cylinder or a multi-cylinder motor.

It is to be observed that the cup-like valve 12 will act as a check-valve to prevent the back flow of water and steam from the generating-and-superheating chamber 7 into the combustion chamber *e*. It will be understood that as the air compressor supplying compressed air through the pipe *m*, reciprocates, there may be caused fluctuations in 55 the pressure in the combustion chamber *e*; and, when the pressure in the latter falls below that in the generating-and-superheating chamber 7, the valve 12 will close and will thereby prevent this back flow of water 60 and steam which would cool the combustion

chamber and interfere with the combustion of the fuel.

I claim:

1. An apparatus of the character described having fuel-feeding devices; means for burning the fuel, said means being provided with a water-jacket; and a generating-and-superheating member in communication with said means and water-jacket. 70

2. An apparatus of the character described having fuel-feeding devices; means for burning the fuel, said means being provided with a water-jacket and a generating-and-superheating member which is in communication with said means and water-jacket and which is provided with devices for breaking up the fluid stream flowing through said member from said means and water-jacket. 75

3. An apparatus of the character described having fuel-feeding devices; means for burning the fuel, said means being provided with a water-jacket; a generating-and-superheating member which is in communication with said means and water-jacket; and links mounted in said member for breaking up the fluid stream flowing through said member from said means and water-jacket. 80

4. An apparatus of the character described having fuel-feeding devices; means for burning the fuel; a generating-and-superheating member which is in communication with said means; and a valve which controls the communication between said means and said member; said means being provided with a water-jacket from which water overflows upon and cools said valve. 95

5. An apparatus of the character described having fuel-feeding devices; means for burning the fuel; a device for supplying water to the products of combustion flowing from said means; and a generating-and-superheating member into which flows the mixture of the products of combustion 100 and water. 110

6. An apparatus of the character described having fuel-feeding devices; means for burning the fuel; a device for supplying water to the products of combustion flowing from said means; and a generating-and-superheating member provided with a foraminated diaphragm through which flow the products of combustion. 115

7. An apparatus of the character described having fuel-feeding devices; means for burning the fuel; a device for supplying water to the products of combustion flowing from said means; and a generating-and-superheating member into which flow 120 the products of combustion and which is provided with a foraminated closure at its outlet end. 125

8. An apparatus of the character described having fuel-feeding devices; means 130

for burning the fuel; a device for supplying water to the products of combustion flowing from said means; and a generating-and-superheating member into which flow the products of combustion and which is provided with foraminated closures at its inlet and outlet ends.

9. An apparatus of the character described having fuel-feeding devices; means 10 for burning the fuel; a generating-and-superheating member into which flow the products of combustion from said means; and means for supplying water to the products of combustion prior to their entrance 15 into said member.

10. An apparatus of the character described having fuel-feeding devices; means for burning the fuel; and a generating-and-superheating member into which flow the 20 products of combustion from said means; the latter being provided with a water-jacket from which water flows into said member.

11. An apparatus of the character described having fuel-feeding devices; means for burning the fuel; a generating-and-superheating member into which flow the products of combustion from said means; and a valve which controls the communication 30 between said means and said member; said means being provided with a water-jacket arranged to supply water to said member and to said valve for cooling the same.

35 12. An apparatus of the character described having fuel-feeding devices; means for burning the fuel; a generating-and-superheating member into which flow the products of combustion from said means 40 and which is provided with a foraminated diaphragm; and a valve which controls the communication between said means and said member through said foraminated diaphragm; said means being provided with a 45 water-jacket arranged below said diaphragm to supply water to said member and to said valve for cooling the same.

13. An apparatus of the character described having fuel-feeding devices; means 50 for burning the fuel; a generating-and-superheating member which is in communication with said means; a valve which controls the communication between said means

and said member; and means for keeping said valve water-cooled.

55 14. An apparatus of the character described having fuel-feeding devices; means for burning the fuel; a device for supplying aqueous fluid to the products of combustion flowing from said means; a generating-and-superheating member into which flow the products of combustion and aqueous fluid; and mechanism for controlling the communication between said member and means.

60 15. An apparatus of the character described having fuel-feeding devices; means for burning the fuel; a device for supplying aqueous fluid to the products of combustion flowing from said means; a generating-and- 70 superheating member into which flow the products of combustion and aqueous fluid; mechanism for controlling the communication between said member and means; and means for cooling said mechanism.

65 16. An apparatus of the character described having fuel-feeding devices; means for burning the fuel; a device for supplying aqueous fluid to the products of combustion flowing from said means; and a generating-and-superheating member into which flow the products of combustion and aqueous fluid and which is provided with heat-transferring devices which retard the flow of 80 said products and transfer heat therefrom 85 to the aqueous fluid.

17. An apparatus of the character described having fuel-feeding devices; means for burning the fuel; a device for supplying aqueous fluid to the products of combustion 90 flowing from said means; a generating-and-superheating member into which flow the products of combustion and aqueous fluid and which is provided with heat-transferring devices which retard the flow of 95 said products and transfer heat therefrom to the aqueous fluid; and mechanism which controls the communication between said member and means.

Signed at New York city, New York, this 100 fifteenth day of March, A. D. 1911, in the presence of the two undersigned witnesses.

OTTO KRAUS.
